UNITED STATES PATENT OFFICE.

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK.

MACHINE FOR BENDING PIPES.

Application filed March 17, 1922. Serial No. 544,580.

To all whom it may concern:

Be it known that I, BROR J. LINDGREN, a citizen of the United States, resident of Buffalo, in the county of Erie and State of New York, have invented new and useful Improvements in Machines for Bending Pipes, of which the following is a specification.

This invention relates to a machine for bending into elbow form pipes which have been previously formed of sheet metal so that the central part of this pipe is provided with circumferential corrugations, while the opposite ends of the same are of cylindrical or uncorrugated form, such elbows being commonly used for conducting the smoke from stoves to chimneys and for similar purposes.

It is the object of this invention to produce a machine whereby such previously corrugated pipes may be bent into elbow form expeditiously, easily and economically and with certainty, so that there will be no imperfect goods which must be discarded as waste.

In the accompanying drawings: Figure 1 is a front elevation of a pipe bending machine embodying my invention, showing the position of the parts which they assume preparatory to bending the same from a straight into an elbow form. Figure 2 is a side elevation of the same. Figure 3 is a top plan view of the same, partly in section. Figure 4 is a fragmentary vertical transverse section, taken on line 4—4, Fig. 3, and showing the position of the parts preparatory to mounting a straight or unbent pipe upon the chucks of the machine. Figure 5 is a view similar to Fig. 4, but showing the parts in the position which they occupy after the bending of the pipe from its straight into elbow form has been completed. Figure 6 is a similar view showing the manner in which one of the chucks is disengaged from the pipe after the same has been bent into elbow-shaped form preparatory to removing the elbow from the machine. Figure 7 is a fragmentary top plan view of the machine, partly in section, showing the movable chuck in its retracted position, preparatory to engaging a pipe in a position similar to that shown in Fig. 4. Figure 8 is a similar view showing the locking mechanism for holding the movable chuck in its operative position. Figure 9 is a vertical transverse

section, taken on line 9—9, Fig. 3 and showing one of the chucks closed upon one end of the pipe which is to be bent into elbow form. Figure 10 is a similar view but showing the chuck opened and the pipe removed therefrom. Figure 11 is a vertical transverse section of the machine taken on line 11—11, Fig. 3. Figure 12 is a perspective view of a finished elbow which has been produced on the machine embodying my invention. Figure 13 is a fragmentary top plan view showing means for adjusting the throw of the chuck arms to permit of making pipe elbows of different angularity. Figure 14 is a cross section of the same taken on line 14—14, Fig. 13.

Similar characters of reference refer to like parts throughout the several views.

The straight or cylindrical pipe blank which is to be operated upon by this machine has its central part provided with a plurality of circumferential corrugations 20 which have been previously compressed to a suitable extent and two plain or uncorrugated cylindrical parts 21 arranged at opposite ends of this pipe, as shown by full lines in Figs. 1, 3 and 4 and by dotted lines in Fig. 12. The operation of the machine forming the subject of this invention results in bending this straight pipe blank into elbow form so that the cylindrical or uncorrugated ends 21 thereof, are arranged at right angles to each other and the corrugations on the central part thereof are squeezed more closely together, while those parts of the corrugations of the outer side or crown 23 of this pipe are pulled or spread apart so that the two cylindrical end portions are connected by an intermediate curved portion, as shown by full lines in Figs. 5, 6 and 12.

To effect such bending of the pipe blank into elbow form the same is first mounted on the two chucks which are engaged with a grip at the opposite uncorrugated ends of the pipe blank while these chucks are axially in line with each other. One of these chucks, for instance, the chuck 24 on the left hand side of the machine, is so mounted that the same is capable only of a vertically swinging motion, while the other chuck 25 on the right hand side of the machine is capable not only of a vertically swinging motion relatively to the other chuck, but also capable of moving lengthwise of its axis

relatively thereto for the purpose of permitting the two chucks to be engaged with the pipe blank previous to bending the latter and thereafter disengaging the pipe blank 5 from the chucks preparatory to bending another.

Although these chucks may be variously constructed, each of the same, as shown in the drawings, preferably comprises a supporting head, a core mounted on the head and adapted to engage with the underside of one of the uncorrugated ends of the pipe blank and a clamp adapted to engage the periphery of the corresponding uncorrugated end of this blank. Each of the supporting heads preferably comprises a vertical transverse base, plate 26 and a bracket 27 projecting forwardly from this base plate. The core is provided with an inner cylindrical end 28 and has its outer end detachably connected with the inner side of the bracket 27 by means of a bolt 29 and the same is also held against turning about its axis on this bracket by one or more keys 30, each of which engages with corresponding grooves or recesses 31, 32, formed in the opposing faces of the bracket 27 and the respective core 28, as shown in Figs. 1, 3 and 7.

30 Each of the clamps, as shown for instance, in Figs. 1, 3, 4, 7, 9 and 10, comprises two curved jaws 33, 34, which practically form two sections of a diametrically split ring and are movable toward and from the upper and lower sides of the periphery of one of the uncorrugated ends of the pipe blank. The clamping jaws are pivotally connected at their corresponding rear ends with the base of the chuck, so as to be capable of 35 swinging vertically toward and from each other, this being preferably accomplished by means of a pivot pin 35 passing through corresponding perforated lugs 36 and 37 formed respectively on the rear ends of the 40 clamping jaws 33 and the adjacent part of the base plate 36. At their front ends these clamping jaws are provided with means whereby the jaws are opened and closed which means in their preferred form consists of the vertically swinging lever 38 45 which is preferably of bifurcated form and pivoted to the front end of the upper jaw 33 and a link 39 pivotally connected at its upper end with the lever 38 and also pivotally connected at its lower end with the front end of the lower jaw, this last-mentioned pivotal connection preferably consisting of a pivot-block 40 pivoted by means of horizontal bolts 41 to ears 42 on 50 the lower clamping jaw and provided with an opening which receives the lower end of the link 39 and screw nuts 43, 44 arranged on the link 39 and engaging with opposite ends of the pivot head 40, as shown in Figs. 55 1, 7, 9 and 10. Upon swinging the lever 38

downwardly the clamping jaws 33 will spread apart, as shown in Fig. 10 and thereby permit one end of the pipe to be inserted between these jaws and the respective core, as well as removed therefrom, while upon 70 swinging this lever upwardly, as shown in Fig. 9, these jaws will be closed or moved toward each other and caused to grip the outer side of the periphery of one end of the pipe blank and holding the same firmly in 75 place on the core within the pipe during the operation of bending the same from a straight into an elbow shaped form. The pivotal connections between the lever 38 and the upper jaw 33 and between this link 80 39 and the lever and the lower jaw are such that when the lever is turned upwardly and rearwardly, the pivotal connection between the link and this lever will be slightly beyond the pivotal connection between the lever 85 and the upper jaw and thus operate to automatically retain these parts in their locked position. By adjusting the screw nuts 43, 44 in the link 39 the clamping jaws may be adjusted relative to the core for producing the desired gripping effect upon a pipe. The lower jaw 34 is preferably provided on its rear part with a stop 45 which is adapted to engage with a part projecting forwardly from the base plate of the chuck, 90 as shown in Fig. 10, and thus cause both jaws to recede from the periphery of the core upon moving the gripping lever 38 downwardly.

95 A vertically swinging movement is imparted to these chucks so that they stand with their axes horizontally in line transversely of the machine previous to and while in engagement with the unbent pipe blank and then these two chucks are swung downwardly into a position in which they stand at substantially right angles to each other for the purpose of bending the pipe from a straight into elbow form. For this purpose two vertically swinging chuck arms 46, 100 47 are provided which have their opposing inner ends pivotally connected with the upper part of an upright frame or standard or pedestal 48 while the outer ends of these 105 chuck arms carry the chucks which grip opposite ends of the pipe blank. Although the pivotal connection between the inner ends of these chuck arms may be varied, this is 110 preferably accomplished by providing the inner end of each chuck arm with a pair of pivot lugs 49, 50, each of which receives a horizontal longitudinal pivot pin 51, each of which is secured at its opposite ends to upwardly projecting lugs 52, 53 on the standard. On the outer parts of the chuck arms, 115 the same are provided with forward extensions 54, 55 upon which the two chucks are mounted so that the latter are arranged in front of the upper part of the pedestal or standard. Instead of mounting the heads 120 125 130

of the chuck directly on the extensions of the chuck arms these heads are mounted indirectly on these arms for convenience in machining and fitting the parts to each other, while manufacturing and assembling the same.

For this purpose supporting plates 56, 57 are employed which are mounted respectively on the front ends of the left and right hand extensions 54 and 55 of the chuck arms and to the front sides of these supporting plates are secured the base plates of the chuck heads. For the purpose of accurately alining the two chucks relatively to each other so that their axes are horizontally in line preparatory to mounting the pipe blank thereon, which is to be bent into an elbow, each of these chucks is provided with means whereby the same may be adjusted vertically on its supporting plate while the chuck is in a horizontal position. As shown in the drawings this vertical adjustment is obtained by means of clamping bolts 58 passing through upright slots 59 in the base plate of each chuck and engaging their ends with the respective supporting plate while their heads bear against the front side of the respective base plates, as shown for instance in Figs. 1, 4-7 and 9 and 10.

In order to permit such vertical adjustment of the chucks relative to the supporting plates and to guide the same during such adjustment as well as to firmly interlock each chuck head and supporting plate so as to relieve the clamping bolts 58 from undue strain, the co-operating surfaces of each chuck head and its companion supporting plate are provided with cooperating vertical guiding surfaces which are constructed to interlock in a horizontal direction this being accomplished in the preferred construction shown in Figs. 1 and 4-7, by means of vertical ribs 60 arranged on the rear side of the base plate of each chuck head and engaging with corresponding grooves 61 on the front side of the companion supporting plate. The supporting plate 56 which carries the left hand chuck is preferably secured permanently to the forward extension 57 of the left hand chuck arm by means of bolts 62, as shown, or by any other suitable means, but the supporting plate 57 which carries the right hand chuck is movable lengthwise or parallel with a radial line of the right hand chuck arm for the purpose of moving the respective chuck away from the left hand chuck and thus provide the necessary clearance between these chucks to permit of placing a blank on the chucks preparatory to bending the same into an elbow and also enabling this pipe to be removed from the chucks after the same has been bent into an elbow form.

The means for guiding the right hand supporting plate for this purpose consists

in providing the forward extension 55 of the right hand chuck arm with a guide rail 63 which has its upper and lower edges beveled, so that it is of dove-tail form in cross section and providing the upper and lower parts of the right hand supporting plate 57 with upper and lower gibs 64, 65 which engage with the upper and lower edges of the guide rail 63 and thereby permit of sliding the right hand supporting plate 57 inwardly and outwardly for the purpose of moving the right hand chuck toward and from the left hand chuck. The lower gib 65 is preferably secured in a definite position to the plate 57 by means of bolts 66 but the upper gib 64 is adjustably mounted on the plate 57 so as to permit of a tight fit of the plate 57 on the guide rail 63 and also enables wear to be taken up. For this purpose horizontal clamping bolts 67 are provided which pass through vertical slots 68 in the upper gib 64 and engage their threaded front ends with the plate 57 while their heads bear against the rear side of the upper gib 64, as best shown in Figs. 10 and 11. The upper gib 64 is pressed toward the guide rail 63 so that the co-operating guiding surfaces of the latter and the gibs 64, 65 and supporting plate 57 fit each other snugly, this being preferably accomplished by means of two tightening screws 69 working in brackets 70 on the rear side of the plate 57 and engaging with the upper edge of the gib 64, as shown in Figs. 2, 3, 7, 9, 10 and 11. The movement of the right hand supporting plate 57 and the corresponding chuck mounted thereon toward and from the left hand supporting head of the chuck is effected preferably by means of a hand operated lever 71 which is pivoted at its rear end to the right hand chuck arm by means of a pin 72 and provided at its front end with a handle 73 which projects upwardly therefrom, while its inner end is connected by means of a link 74 with the outer end of the supporting head 57. While the right hand chuck is moved inwardly into its operative position in which it supports the right hand end of the pipe blank, as shown in Figs. 1 and 3, means are provided for locking the parts in this position so that the chucks will not become separated during the operation of bending the straight pipe blank into elbow shape.

The preferred locking device for this purpose comprises a catch 75 arranged within a recess 76 in the right hand chuck arm and pivoted at its inner end thereto by means of a pin 77 while its outer end is provided with a hook 78 which is adapted to engage with a shoulder 79 on the hand operated lever 71. The hook of this catch is provided with a beveled surface 80 and the same is yieldingly held in its forward position by means of a spring 81 arranged

in the recess 76 and bearing at its opposite ends against the catch 75 and the adjacent part of the supporting arm 47 so that upon swinging the hand lever 71 inwardly the 5 hook 78 will engage automatically with the shoulder 79 and thereby hold the longitudinally movable chuck in its operative position. This catch is released from the hand lever 71 preparatory to swinging the 10 latter outwardly for moving the right hand chuck away from the left hand chuck, this being accomplished by means of a trigger lever 82 pivoted on the hand lever 71 having its handle arranged adjacent to the 15 operating handle 73 while its lower arm is connected with the shifting rod 83 which extends lengthwise of the operating lever 71 and is guided in a lug 84 on the underside thereof and is adapted to bear with its 20 rear end against the free end of the catch 75 for disengaging the hook of the catch from the shoulder 79, as shown in Fig. 8. In the act, therefore, of grasping the handle 73 the trigger 82 is also operated and therefore automatically releases the catch 75 to 25 permit the hand lever 71 to be swung outwardly by the use of one hand and practically one operation.

The downward and upward swinging 30 motion in the preferred construction of this machine is imparted to the chuck supporting arms by means of a crank shaft 85 which is journaled horizontally and lengthwise in suitable bearings in the lower part 35 of the standard or main frame and provided on its central part with a crank 86 which latter is connected by means of right and left hand connecting rods 87, 88 with the right and left hand chuck arms between 40 their inner pivoted ends and chucks on the outer edge of the same. The elevated position of the chuck arms in which the axes of the two chucks are raised horizontally in line, the crank 86 of the crank shaft is 45 in its highest position, as shown in Figs. 1, 2 and 11. Upon turning the crank shaft a half turn so that its crank is in its lowermost position the two chuck supporting arms will be both turned downwardly so 50 that they stand substantially at right angles to each other, as shown in Fig. 5. Thereafter another half turn of the crank shaft will bring its crank again to its uppermost position and restore the chucks to 55 their horizontal aligned position. This rotary movement is imparted to the crank shaft by means which comprise a horizontal driving shaft 89 which is journaled lengthwise in suitable bearings on the main frame 60 and provided with a gear pinion 90 which meshes with a gear wheel 91 having twice the diameter of the gear pinion and secured to the rear end of the crank shaft, as shown by full lines in Fig. 2 and by dotted lines 65 in Fig. 1. The driving shaft is operated by

means of a belt passing around a pulley 92 which is arranged on the rear end of the driving shaft and adapted to be connected with and disconnected from the driving shaft by means of a clutch 93 which latter is preferably coupled upon operating a treadle 94 which is operatively connected with this clutch which at the end of each rotation of the pulley 92 the same is automatically uncoupled from this driving shaft. 70 It follows from this that for each depression of the treadle 94 the crank shaft will make a half rotation so that by depressing this treadle once the chucks will be swung from their upper horizontal position to their lower angular position relatively to each other, and upon another depression of this treadle these chucks will be again raised from their lower angular position to their 75 elevated position in which they are horizontally in line.

As shown in Fig. 10, the stop 45 of the lower jaw of one of the chucks engages with the adjacent clamping bolt 58 for limiting the descent of this jaw of the opening 90 movement of the same and its companion upper jaw 33, but obviously this opening movement of the jaws may be limited by engagement of the stop 45 with any other suitable abutment on the respective chuck. 95

In the operation of this machine, one end of a straight pipe blank is first slipped over the core of the left hand chuck while the right hand chuck is moved lengthwise away from the left hand chuck to provide the necessary clearance for this purpose, as shown in Fig. 4. The hand lever 71 is then swung inwardly so as to engage the core of the right hand chuck with the corresponding end of the pipe blank, as shown in Figs. 100 1 and 3. The clamping jaws 33 and 34 may be closed upon the left hand end of the pipe blank either before or after the left hand core is inserted into the corresponding end of the pipe blank and after the 110 left hand core has been inserted in the pipe blank the clamping jaws 33, 34 of the right hand chuck are also closed upon the exterior of the pipe blank. The treadle 94 is now depressed so that the crank 86 moves 115 from its uppermost to its lowermost position and then comes to rest by reason of the automatic operation of the clutch 93 whereby the chucks are moved from the upper horizontally aligned position shown in Fig. 1 to their lower position in which they are 120 arranged at an angle relatively to each other, as shown in Fig. 5.

Thereafter the clamping jaws 33, 34 of the right hand chuck are released from the 125 elbow shaped pipe and the hand lever 71 is unlocked and swung outwardly whereby this chuck is disengaged from the corresponding end of the elbow-shaped pipe as shown in Fig. 6. Upon now disengaging the clamp- 130

ing jaws 33, 34 of the left hand chuck from the elbow-shaped pipe the latter which is now completed, may be easily removed from this chuck. The treadle is now again depressed whereby the two chucks are shifted from the inclined and separated position shown in Fig. 6 to the horizontally aligned and separated position, shown in Fig. 4, ready to receive the next pipe blank, which is to be bent into elbow-shape. The extent of the downward movement of the two chucks is preferably slightly greater than ninety degrees so that when the pipe blank is bent from its straight form into elbow form, the ends of the elbow-shaped pipe are thereby also bent slightly more than at right angles to each other, so as to compensate for the resilience of the metal which tends to spring back slightly after the bending operation has been completed and thereby insure leaving the finished product in a condition in which the two ends of the elbow are at right angles or substantially so relatively to each other. During the bending operation of the pipe blank from a straight into an elbow form, the corrugations on the inner side or throat of the same are pressed together somewhat closer than they were in the blank and the corrugations on the outer side or crown of the pipe are spread or pulled apart the requisite extent to form the elbow.

For the purpose of limiting the extent of movement of the chuck 25 away from the chuck 24 a stop 95 is provided on the right hand chuck arm which is engaged by the right hand supporting plate 57, as shown in Figs. 6 and 7.

In practice the overlapping edges of the sheet metal blank from which the pipe is constructed are arranged on the inner and throat side of the pipe so that the operation of closing the corrugations on the throat side of the elbow operates to securely unite the overlapping edges of the pipe and avoid the necessity of any special fastening for this purpose.

When the rods or links 87, 88 are connected with the chuck arms 46 and 47 so that the pivotal connection between these members can not be adjusted, as shown in Figs. 3 and 11, it is possible to move the chucks only between two definite extreme positions relative to each other and thus permit of producing pipe elbows of one angle only.

In order to enable the same machine to be used for bending pipe elbows of different angularity, means are provided whereby the pivotal connections between the connecting rods 87 and 88 and the chuck arms 46, 47 may be adjusted toward and from the axes of the latter. In Figs. 13 and 14 are shown means which are suitable for this purpose and as there shown the same comprise two pivot blocks 96, 97 which are connected re-

spectively with the pivot pins 98, 99 of the connecting rods 87, 88, and are slideable on the undersides of segments 100, 101 formed on the arms 46, 47 concentric with the axes thereof and adjustably connected therewith by bolts 102, 103 secured to the pivot blocks and passing through longitudinal slots 104, 105 in said segments. By adjusting the pivot pins 98, 99 toward the axes of the chuck arms the sweep of the chucks will be increased and produce greater angularity between the ends of the pipe elbow but when these pivots are moved away from the axes of these arms the throw of the chucks is reduced and the angle between the ends of the pipe elbow produced thereby will be correspondingly less. It is therefore possible by means of this adjustment to produce pipe elbows of any desired angle within predetermined limits to suit different requirements.

As a whole this machine is strong, durable and compact in construction, the same can be operated with a minimum expenditure of manual labor or power and permits of producing pipe elbows expeditiously and at low cost.

I claim as my invention:

1. In a machine of the character described, a standard, two chuck arms having their inner ends pivotally connected with opposite sides of the standard by horizontal longitudinal pivots and provided on their outer ends with forward extensions, supporting plates arranged on said extensions, chucks adapted to engage opposite ends of a pipe and each having a head and slots in said head arranged transversely of the axis of the respective chuck and clamping bolts passing through said slots and into said plates.

2. In a machine of the character described, a standard, two chuck arms having their inner ends pivotally connected with opposite sides of the standard by horizontal longitudinal pivots and provided on their outer ends with forward extensions, supporting plates arranged on said extensions, chucks adapted to engage opposite ends of a pipe, means for adjusting each of said heads on one of said plates transversely of the axis of the respective chuck, and each of said heads and companion plate being provided with co-operating interlocking guide surfaces extending transversely of the axis of the respective chuck.

3. In a machine of the character described, a standard, two chuck arms having their inner ends pivotally connected with the opposite side of the standard by horizontal longitudinal pivots and provided on their outer ends with forward extensions, a chuck normally immovable on the extension of one of said arms and adapted to engage one end of a pipe, a chuck adapted to engage the other end of said pipe and movable on the

- extension of the other arm in a direction parallel with a radial line thereof, and means for moving said last-mentioned chuck radially on its arm extension. 55
- 5 4. In a machine of the character described, a standard, two chuck arms having their inner ends pivotally connected with opposite sides of the standard by horizontal longitudinal pivots and provided on their outer ends with forward extensions, a chuck normally immovable on the extension of one of said arms and adapted to engage one end of a pipe, a chuck adapted to engage the other end of said pipe and movable on the extension of the other arm in a direction parallel with a radial line thereof, means for moving said last-mentioned chuck radially on its arm extension comprising a lever pivoted on the respective arm and a link connecting said lever with the respective chuck, a catch mounted on said last-mentioned arm and adapted to engage with said lever for holding the respective chuck in its operative position, and means for disengaging said catch from said lever comprising a shifting rod guided on the lever and adapted to engage one end with said catch and a trigger arranged on the lever adjacent to the handle thereof and engaging with the opposite end of said shifting rod. 60
- 10 5. In a machine of the character described, a standard, two chuck arms having their inner ends pivotally connected with opposite sides of the standard by horizontal longitudinal pivots and provided on their outer ends with forward extensions, a chuck normally immovable on the extension of one of said arms and adapted to engage one end of a pipe, a chuck adapted to engage the other end of said pipe and movable on the extension of the other arm in a direction parallel with a radial line thereof, means for moving said last-mentioned chuck radially on its arm extension comprising a lever pivoted on the respective arm and a link connecting said lever with the respective chuck, a catch mounted on said last-mentioned arm and adapted to engage with said lever for holding the respective chuck in its operative position. 65
- 15 6. In a machine of the character described, a standard, two chuck arms having their inner ends pivotally connected with opposite sides of the standard by horizontal longitudinal pivots and provided on their outer ends with forward extensions, a chuck normally immovable on the extension of one of said arms and adapted to engage one end of a pipe, a chuck adapted to engage the other end of said pipe and movable on the extension of the other arm in a direction parallel with a radial line thereof, means for moving said last-mentioned chuck radially on its arm extension comprising a lever pivoted on the respective arm and a link connecting said lever with the respective chuck, a catch mounted on said last-mentioned arm and adapted to engage with said lever for holding the respective chuck in its operative position. 70
- 20 7. In a machine of the character described, two chucks adapted to engage opposite ends of a pipe, carriers supporting said chucks and having fixed pivots about which they are movable into different angular positions relatively to each other, and means for adjusting the stroke of said carriers for varying the angle of the pipe ends relatively to each other. 75
- 25 8. In a machine of the character described, two chucks adapted to engage opposite ends of a pipe, carriers supporting said chucks and pivoted at fixed points so as to be capable of moving the chucks into different angular positions relatively to each other, a crank shaft having a crank, connecting rods connected at one end with said crank, and means connecting the opposite ends of said rods with said carrier and permitting of shifting the connection between each rod and carrier toward and from the axis of the latter for varying the angle of the pipe ends relatively to each other. 80
- 30 9. A machine of the character described, comprising a frame, two chuck arms pivoted at fixed points on said frame and each provided with slots, chucks mounted on said chuck arms and adapted to support opposite ends of a pipe, a rotary crank, connecting rods pivotally connected at one end with said crank, and bolts adjustable in said slots and connecting said rods with said chuck arms for varying the angle of the pipe ends relatively to each other. 85
